UNITED STATES PATENT OFFICE.

ALFONS MAUSER, OF COLOGNE-MARIENBURG, GERMANY.

METAL-WORKING MACHINE.

Application filed December 12, 1925, Serial No. 74,991, and in Germany January 15, 1925.

This invention relates to metal working machines and has for its principal object to provide a new and improved machine particularly adapted for perfecting the seams of sheet metal articles. Considered more specifically, one of the objects of the invention is to provide a machine for pressing or finishing the lapped seam usually employed for joining two ends of a sheet or sheets of metal together in the manufacturing of sheet metal articles. Another object is to provide a machine capable of being interchangeably used for perfecting or finishing a welded seam as well as a folded or lapped seam. A further object is to provide a built up frame construction for the machine which avoids the use of solid castings for the main frame, thereby securing a frame capable of being manufactured at a comparatively low cost, and which, while possessing a certain amount of elasticity to permit a limited amount of yielding of the frame to compensate for irregularities in the material being worked upon, is of sufficient rigidity to insure a substantially even or constant pressure upon the work.

Other objects will appear from the following more detailed description and by reference to the accompanying drawings, in which Fig. 1 is a side elevation partly in section of a constructional example of a machine embodying the principles of my invention; Figs. 2, 3 and 4 are sections on the lines 2—2, 3—3 and 4—4 of Fig. 1; Figs. 5 and 6 are enlarged sectional details of the rolls shown in Figs. 2 and 3 respectively showing the manner in which the pairs of rolls perform their respective functions in perfecting a seam; and Fig. 7 is a view similar to Figs. 5 and 6, showing the outline or profile of the rolls used for perfecting a welded seam.

As shown in the drawings, the frame of the machine consists of a pair of side members 10, constructed of sheet metal, each having a U-shaped slot 11 extending approximately horizontally of the frame and midway between the top and bottom thereof, the open end of the U being at the front of the machine. The side members are connected in spaced relationship by channel irons 12, 13 and 14, to which said members are suitably secured as by the rivets 15, said irons serving to strengthen and brace the frame, as well as to connect the members 10.

The iron 12 extends along the top and back edge of the frame, the iron 13 along the bottom, and the iron 14, which is bent to form a U, extends around the edge of the U slot 11, as clearly shown in Fig. 1.

Each of the channel irons 12, 13 and 14 terminate a short distance from the front of the machine to leave a space in which the roller carrying brackets 16 and 17 are mounted. Each of said brackets carries rollers to be hereinafter more fully described, and one of said brackets is stationarily held in its respective arm, while the other is movable in its arm for adjusting one set of rollers to and from the other set. As shown, the top bracket is rigidly secured to the frame in any suitable manner, as by the bolts 18, while the bottom bracket 17 is slidably mounted between the inner faces of the side members or sheets 10. Projecting outwardly from each side of the bottom bracket is a lug 19 engaging slidably within a vertical slot 20, provided in the side sheet 10.

Rotatably mounted in a bearing bracket 21, bolted between the side sheets 10 at the lower front end thereof, is a worm shaft 22 having a hand wheel 23 secured to its front end, and a worm 24, secured to its rear end. The worm 24 engages within threads cut in the lower rear face of a wedge 25 which extends slidably between the lower roller bracket 17 and the bearing bracket 21.

Mounted rotatably in the roller brackets 16 and 17 are two co-operating pairs of seam pressing or forming rollers, the front pair consisting of two similarly shaped rolls 26, 27, each having a flange at one side thereof, and the flanges being oppositely arranged to define a central recess 28 between them, while the rear pair of rolls consists of a cylindrical roll 29 of uniform diameter, and a flanged roll 30, having a central recess 31 therein, located immediately behind and in alignment with the recess 28 defined by the front rolls.

I prefer to provide means for driving one set of rollers in order that the rollers may function to pull or feed the article inwardly, while the pressing operation is being performed. As shown, a counter-shaft 32 having a pulley 33 on its outer end is journaled in the frame transversely thereof. The inner end of said counter-shaft carries a bevel gear 34 meshing with a bevel gear 35 on the rear end of a longitudinal shaft 36, the

front end of which has a bevel gear 37 secured to it. The bevel gear 37 meshes with a similar gear 38 on a jack shaft 39 which drives the top rollers by means of the spur gears 40.

The operation of the machine is as follows: Assuming that a lapped or folding joint is being formed to connect the ends of a single sheet to form it into a hollow cylinder such as indicated at 41 in Fig. 1, and that it is desired to press the folds 36 (Figs. 5 and 6) of such joint into tight engagement and otherwise to perfect the joint; the lower roller bracket 17 is adjusted by means of the hand wheel 23, worm 24 and wedge 25 to bring the faces of the pairs of rollers to the proper position to exert the desired pressure on the work. The work is then inserted into the U slot of the frame with the seam 10 in the central recesses 28 and 31, and is pushed rearwardly. The front rolls, as shown more clearly in Fig. 5, press the folds of the seam into tight engagement, and also presses the seam flat against the side of the sheet 20 in such condition that the rear rolls can readily complete the perfecting of the seam. The rear rolls complete the seam by pressing the sheet upwardly about one side of the seam until the folded seam lies entirely on one side of the article only, preferably the inner side.

The machine may also be employed for finishing a welded seam in which case the plain faced rollers 45 are substituted for the flanged rollers shown in Figs. 2 and 3. The rollers 45, as shown in Fig. 7, are preferably curved slightly on their active or working faces. When using the machine with the rollers 45 on welded seams, the rollers 45 will press down upon the seam and tend to flatten out any irregularities in the seam and at the same time will thoroughly remove the scale, due to the welding operation.

With a machine constructed in accordance with my invention, it will be seen that the finishing of the seams may be accomplished with great rapidity, the folds of the finished seam being pressed tightly together to form a very strong, tight joint. In addition, the projecting part of the finished seams will be located inside of the container so as to be protected from exterior blows or shocks. Moreover, all of the seams will be of substantially the same size, thereby insuring 50 regularity in the appearance of the finished articles. It will also be seen that as a result

of constructing the frame in the manner set forth, due to the length of the frame arms, sufficient resiliency of said arms is secured to enable the rollers to yield and compensate 60 for irregularities in the work. As such irregularities are relatively small, the arms will move but such a short distance that the pressure exerted on the work will be constant. 65

Various modifications may be made without departing from the nature of my invention as set forth in the appended claims.

I claim:

1. A machine of the character described, 70 comprising a frame, opposing companion rollers journaled therein and arranged in a plurality of successively operating pairs, the rollers of one pair being both flanged, but at opposite sides, to form a guide groove for 75 the longitudinal, previously formed, lapped seam of a sheet metal article fitted between said rollers and to give an initial closing pressure to said seam while bending it into the plane of the metal of the article, while 80 in another pair one of the rollers has a smooth periphery and the other two spaced flanges to form a groove for the reception and guidance of the aforesaid longitudinal seam whereby the metal forming the laps of 85 the seam is forced to lie entirely on one side of said plane and a final compression is exerted both laterally of the sides of the seam and transversely across the laps thereof.

2. In a seam finishing machine, a built-up 90 frame consisting of a pair of sheet metal side sheets, each provided with a horizontally extending open-ended slot, and means for securely connecting said members in spaced relationship, said means including upper 95 and lower pressed steel, channel iron braces extending along the upper and lower edges of said members substantially in parallelism with said slot, and a pressed steel, channel iron brace extending around and closely adjacent to said slot, said braces and the sheet metal sides providing a structure having a limited degree of resiliency which enables said frame to yield slightly to compensate for irregularities in the work operated upon by said machine while maintaining a substantially even pressure on said work. 100

In testimony whereof I have hereunto set my hand.

ALFONS MAUSER.
